DESIGN.

E. H. HILL.

CARPET.

No. 18,113.

Patented Feb. 28, 1888.

UNITED STATES PATENT OFFICE.

EUGENE H. HILL, OF PHILADELPHIA, PENNSYLVANIA, ASSIGNOR TO SCHOFIELD, MASON & CO., OF SAME PLACE.

DESIGN FOR A CARPET.

SPECIFICATION forming part of Design No. 18,113, dated February 28, 1888.

Application filed January 20, 1888. Serial No. 261,396. Term of patent 3½ years.

To all whom it may concern:

Be it known that I, EUGENE H. HILL, a citizen and resident of the city of Philadelphia, State of Pennsylvania, have invented or 5 produced a new and original Design for a Pattern to be Inwrought into Body-Brussels and other Carpeting; and I do hereby declare that the photographic illustration accompanying this specification gives and conveys to any one 10 skilled in the art of carpet-weaving a defined and thorough description of the nature of my invention, that is sufficient to enable any one so skilled to use my invention.

What I claim as my invention, and desire to secure by Letters Patent, is—15 The design for carpets, as shown in the photographic illustration accompanying this specification.

EUGENE H. HILL.
